UNITED STATES PATENT OFFICE.

JOHN PAKENHAM, OF BROOKLYN, NEW YORK.

DESIGN FOR ALTO-RILIEVO.

SPECIFICATION forming part of Design No. 16,334, dated October 13, 1885.

Application filed July 13, 1885. Serial No. 171,542. Term of patent 7 years.

To all whom it may concern:

Be it known that I, JOHN PAKENHAM, of Brooklyn, in the county of Kings and State of New York, have invented and produced a new 5 and original Design for Alto-Rilievo, of which the following is a full, clear, and exact description.

Reference is to be had to the accompanying drawing, forming part of this specification, and 10 which is a front elevation of my newly-designed alto-rilievo.

The leading feature of my design consists of 15 the picture of a steamship, in which the hull, sails, ropes, smoke-stacks, and other appliances are in relief in a depressed field. The depressed field is oval in contour, and is on a rectangular panel, having a depressed bead or molding on the edge thereof. The steamship

is represented as sailing over rough water, which forms the foreground of the picture, 20 and which is also in relief. Above the steamship is the representation of clouds in relief, and which form the background of the picture.

I claim—

25 In a design for alto-rilievo, the rectangular panel having a depressed marginal bead or molding and an oval depressed field, and the picture of a steamship represented as sailing through rough water with clouds in the background, the steamship, water, and clouds being in relief, as shown and described.

JOHN PAKENHAM.
